UNITED STATES PATENT OFFICE.

STEPHEN STEPANIAN, OF COLUMBUS, OHIO, ASSIGNOR TO THE JEFFREY MANUFACTURING COMPANY, A CORPORATION OF OHIO.

COAL-WASHER.

1,084,909.

Specification of Letters Patent.

Patented Jan. 20, 1914.

Application filed September 7, 1909. Serial No. 516,331.

To all whom it may concern:

Be it known that I, STEPHEN STEPANIAN, a citizen of the United States, residing at Columbus, in the county of Franklin and 5 State of Ohio, have invented certain new and useful Improvements in Coal-Washers, of which the following is a specification, reference being had therein to the accompanying drawings.

10 This invention relates to coal washing devices in which the separation of the impurities or refuse matter is effected by subjecting the material in the washing tank or vessel to agitation, or the action of water currents, or both, and the principal object of the invention is to provide automatically operating devices for periodically drawing or discharging the refuse matter.

The invention is well adapted for use in 20 connection with coal washers of the type shown in Patent No. 702,897 granted June 17, 1902, and in the accompanying drawings I show it embodied in a coal washing machine of this kind.

25 Of the drawings Figure 1 is a side elevation of the valve actuating mechanism, with the refuse chamber and valves shown in section. Fig. 2 is a horizontal section taken along the line 2—2 of Fig. 1. Fig. 3 is an 30 end elevation of the valve actuating mechanism, together with the lower parts of the washing mechanism proper. Fig. 4 is a side elevation of the valve actuating mechanism opposite that shown in Fig. 1.

35 Referring to the drawings, A is a washing vessel or tank of suitable form having a contracted lower end. Preferably it is of the frusto-conical form shown. At its upper end the vessel A is open and adapted 40 to receive the coal or other material to be washed. The material may be fed in any desired manner to suit the requirements of the washer in its speed of operation and the withdrawal of washed or separated material therefrom.

F is a water chamber or ring surrounding and attached to the lower end of the washer, communicating therewith through a perforated wall or plate f and water supply pipes F'. The water thus supplied to the washer is after the washing operation conducted away, with the lifted or suspended lighter or finer impurities or separated materials, by an opening a near the 50 top of the washer and suitable conduits.

The chamber F has a short downward cylindrical extension F², terminating in a horizontal flange f². Bolted to the latter is a horizontal frame G, which I term the "valve-frame". It is cast and finished in the form 60 shown in Figs. 2, 3, 4 and 5. It comprises a horizontal web or plate g, having a central aperture g' in line with the chamber of the extension F², which web is secured to the flange of the latter by the bolts g². Between the holes for said bolts the frame is formed on its under side with a longitudinal recess g³, extending from end to end of the frame and adapted to receive between its side walls g⁴ a closely-fitting valve 65 70 II, formed with an aperture h corresponding with that at g' in the valve-frame. The valve may be moved longitudinally by means hereinafter described, so that its aperture h may coincide with the aperture 75 g' to permit the escape of material from the washer, or so as to lie beneath the imperforate plate g and bring the imperforate portion h' of the valve across the aperture g' to tightly close this exit from the washer. 80

I is a plate coöperating with frame G to closely hold the valve II except as to its longitudinal movement above described. It lies beneath the valve-frame and is secured to the latter by bolts i along its sides. The 85 bolts g² hold securely together not only the horizontal flange f², the valve frame G and the bottom plate I but also pass through and fasten to these several parts, the upper flange 1 of the pipe 2 which surrounds the refuse 90 chamber 4. A lower valve mechanism 5 similar in all respects to the upper valve mechanism, already described, is arranged at the lower end of the pipe 2 and secured thereto. In alignment with the pipe 2 and 95 upon the lower side of the valve mechanism 5 is secured the discharge nozzle 6.

The entire machinery is supported on two cast iron vertical side frames 37 having all the necessary bearings cast thereon with removable caps. The gib plates 31 and 32 attach the two frames together in a substantial way.

The upper valve is opened and closed by a complete revolution of a crank 12 which is 105 pivotally connected to the valve by a connecting bar 8. This crank 12 which operates the upper valve is mounted on a shaft 15 supported in bearings 15', 15', formed in the frames 37. The hub of crank 12 is 110

2
loose on shaft 15. The hub of the adjacent crank 13 is key-seated on shaft 15 and the two cranks are attached by a breaking pin 13'. Thus if the valve is stopped while 5 being closed, by contact with some hard object, the pin holding the cranks together will break and let the shaft turn loose in the hub of the crank, thus preventing any serious injury to the machine. A spur pinion 17 is also mounted on the shaft 15. This 10 spur pinion meshes with an intermittent gear 18 which is twice the diameter of the spur pinion, but has the same number of teeth as the pinion. It is mounted on shaft 19, 15 which is revolubly supported in bearings 19', 19' formed in frames 37. Below this intermittent gear there is mounted another 20 spur pinion 21 with the same number of teeth and diameter as spur pinion 17. This 25 pinion which is mounted on a lower shaft 24 is also in position to mesh with the teeth of the intermittent gear. Shaft 24 is revolubly supported in bearings 24', 24' formed in side frames 37. At its end there 30 is secured another crank 12' which is attached to the lower valve 5 by a connecting 35 bar 8'.
When the intermittent gear revolves in the direction indicated by the arrow it engages 40 the upper spur pinion 17 and gives the latter a complete revolution. The crank 12, being on the same shaft, also makes a complete revolution and thus gives first a backward 45 and then a forward movement of reciprocation to the connecting rod 8 and, by means of it, to the upper valve H. During the backward movement of the crank the valve 50 opens and permits the refuse which has accumulated in the bottom of the washer tank A to drop into refuse chamber 4. By the forward movement of the crank the valve 55 is closed and the refuse is trapped between the upper and the lower valves.

When the intermittent gear disengages 45 from the upper pinion 17 it engages immediately the lower spur pinion 21 and gives a complete revolution to it also. The crank 12 at the end of this shaft by its rotation 50 opens and closes the lower valve 5. Thus the refuse which was trapped in refuse 55 chamber 4 is discharged through the nozzle 6. On the intermittent gear shaft 19 there is mounted a spur pinion 20. This pinion meshes with a spur gear 22 which has four 60 times as many teeth as the spur pinion 20. When the spur gear 22 makes one quarter of a revolution the spur pinion 20 makes one complete revolution and turns the intermittent gear through one revolution also. The 65 spur gear 22 is keyed upon shaft 25 which is mounted in bearings 25' formed in the side frames 37, 37. A star wheel 23 with four notches is also mounted on shaft 25. The notches of this star wheel are engaged 70 by steel rollers 39 which are revolubly

mounted on pins 40. Each of these pins is secured between two of the lugs 41 on disk wheel 26. This disk wheel has twelve 75 equally spaced pairs of lugs 41 apertured to receive and support the pins 40.

The drawing shows the disk wheel 26 with but one roller 39 and pin 40 mounted thereon, the roller being just about to engage a notch of the star wheel. This roller 39 gives a 80 quarter revolution to the star wheel and shaft 25. The spur gear 22 being keyed to the same shaft also makes a quarter revolution, and it gives a complete revolution to the intermittent gear shaft 19 by means of the pinion 20. When the intermittent gear makes a complete revolution it first meshes with the upper spur pinion 17 opening and closing the upper valve H, and then, disengaging from the upper pinion, it engages the lower pinion 21, which in turn makes a 85 complete revolution and opens and closes the lower valve 5. After the intermittent gear disengages from the lower pinion it remains in the position shown in Fig. 2 until the roller on the disk wheel next engages 90 and gives another quarter revolution to the star wheel 23.

Assuming that the disk wheel makes one revolution in twelve minutes, the interval 95 between the "draws" of refuse can be regulated from one minute to twelve minutes by adjusting in position as many rollers on the disk wheel as may be required. The shaft 28 on which the disk wheel is mounted is supported in bearings 28' in the side frames 100 37, and has a worm wheel 27 secured to it. The worm 29 which drives this worm wheel is rigidly mounted on a vertical shaft 33, which is held in place by the vertical bearing 31' and step box bearing 32. These 105 bearings are formed in the cast gib plate extensions 31 and 32 respectively, which are bolted to the supporting side frames 37 of the machine. A bevel gear 34' is mounted at the upper end of this vertical shaft 33 110 which meshes with the bevel pinion 34, the latter being mounted on shaft 35. This shaft is provided at its end with a driving sprocket 36 of such diameter as to give the proper speed to the valve mechanism. This 115 sprocket receives its power by chain belting from any suitable power source and transmits it to the valve operating device.

By the mechanism of my invention, means 120 is provided for automatically operating the upper valve and the lower valve of a refuse chamber at definite intervals. These intervals are at the same time adjustable to suit the number of refuse "draws" necessary 125 to clean coal of varying quality and mixed with a varying amount of dirt and other foreign matter. For many reasons it is desirable to have this certainty of valve operation at definite intervals of time. For instance the devices used for conveying the re- 130

fuse away from the washer can be loaded in an efficient and satisfactory manner without waste of material or clogging of the moving parts.

5. What I claim is—

1. The combination of a valve operating mechanism adapted in one cycle of operations to open and close first one and then the other of two series arranged valves, a constantly moving power element, and mechanism adapted to intermittently transmit power from the power element directly to the valve operating mechanism to move it sufficiently at each actuation to effect a complete cycle of valve movements.

2. The combination of a valve operating mechanism adapted in one cycle of operations to open and close first one and then the other of two series arranged valves, a constantly moving power element, and mechanism adapted to intermittently transmit power from the power element directly to the valve operating mechanism to move it sufficiently at each actuation to effect a complete cycle of valve movements, the said power transmitting mechanism being adjustable to vary the intervals between successive periods of power transmission.

3. In a valve operating mechanism for opening and closing first one and then the other of two valves arranged one above the other, the combination of a constantly rotating power shaft, a train of power transmitting gearing, means for intermittently connecting said gearing with the power shaft, and means for alternately connecting the said gearing at its other end first with the upper valve to open and close the same and then similarly with the lower valve.

4. In a valve operating mechanism for opening and closing first one and then the other of two valves arranged one above the other, the combination of a constantly rotating power shaft, and a train of power transmitting gearing intermittently driven by the said power shaft and alternately operating the upper and lower valves respectively.

5. In a valve operating mechanism for opening and closing first one and then the other of two valves arranged one above the other, the combination of a gear wheel and machine elements driven thereby adapted to open and close the upper valve, a second gear wheel and elements driven thereby adapted to open and close the lower valve, an intermittent gear wheel mounted in position to engage first one gear wheel and then the other, and means for operating the said intermittent gear wheel.

6. In a valve operating mechanism for opening and closing first one and then the other of two valves arranged one above the other, the combination of a gear wheel and machine elements driven thereby adapted to open and close the upper valve, a second gear

wheel and elements driven thereby adapted to open and close the lower valve, an intermittent gear wheel mounted in position to engage first one gear wheel and then the other, and means for intermittently operating the said intermittent gear wheel.

7. In a valve operating mechanism for opening and closing first one and then the other of two valves arranged one above the other, the combination of means for alternately opening the said valves, a star wheel adapted in one revolution to effect a given number of cycles of valve operation and having the same number of engaging projections as the said given number of cycles, and a power wheel having a series of projections mating with the projections on the star wheel, any one or all of which projections in the power wheel can be rendered inoperative.

8. In an apparatus of the class described, the combination of a reciprocating valve, a crank and crank shaft for reciprocating said valve, a gear wheel for driving the crank shaft, a second reciprocating valve, a second crank and crank shaft for operating the second valve, a second gear wheel for driving the second crank shaft, each gear wheel being adapted during one revolution to cause the opening and closing of its corresponding valve, an intermittent gear wheel mounted between the said gear wheels and having teeth formed upon one half of its periphery only and adapted to mesh with one of the said gear wheels during one-half of its revolution and with the other of said gear wheels during the other half of its revolution, and driving mechanism for said intermittent gear wheel.

9. In an apparatus of the class described, the combination of a reciprocating valve, a crank and crank shaft for reciprocating said valve, a gear wheel for driving the crank shaft, a second reciprocating valve, a second crank and crank shaft for reciprocating the second valve, a second gear wheel for driving the second crank shaft, each gear wheel being adapted during one revolution to cause the opening and closing of its corresponding valve, an intermittent gear wheel mounted between the said gear wheels and having teeth formed upon one-half of its periphery only and adapted to mesh with one of the said gear wheels during one-half of its revolution and with the other of said gear wheels during the other half of its revolution, and driving mechanism for said intermittent gear wheel.

10. In an apparatus of the class described, the combination of a reciprocating valve, a crank and crank shaft for reciprocating said valve, a gear wheel for driving the crank shaft, a second reciprocating valve, a second crank and crank shaft for reciprocating the second valve, a second gear wheel for driving the second crank shaft, each gear wheel being adapted during one revolution to cause the opening and closing of its corresponding valve, an intermittent gear wheel mounted between the said gear wheels and having teeth formed upon one-half of its periphery only and adapted to mesh with one of the said gear wheels during one-half of its revolution and with the other of said gear wheels during the other half of its revolution, a star wheel for driving said intermittent gear through a plurality of revolutions for each revolution of its own and having the same number of teeth upon its periphery as the number of revolutions which it imparts to the said intermittent gear, and a driving wheel for intermittently engaging said star wheel.

10. In a valve operating mechanism for

opening and closing first one and then the other of two valves arranged one above the other, the combination of means for alternately operating the said valves comprising a star wheel and means for transmitting power from the star wheel alternately to the valves, and a power wheel having a series of pins mounted at equal intervals around its

periphery for engagement with the star wheel and readily movable therefrom. 10

In testimony whereof I affix my signature, in presence of two witnesses.

STEPHEN STEPANIAN.
